GARMENT HANGER

Philip Friedman, New York, N. Y.

Application March 8, 1935, Serial No. 9,945

3 Claims. (Cl. 223—98)

This invention relates to improvements in garment hangers and more particularly to a jacket or cover attachment for garment hangers of the wire variety.

One of the main features of the invention resides in a cardboard cover or jacket for use in association with the wire type of garment hanger to prevent the narrow gage wire of which such hangers are constructed from causing creases 10 to appear in coats, pants, dresses, ties, or other apparel which may be hung thereon.

Another object of the invention is to provide a cardboard cover for wire garment hangers which is inexpensive and on which an advertisement may appear, thus making such type of garment hangers attractive for advertising purposes by tailors, valet service establishments, haberdashers, dress shops, and other like business concerns.

A further object of the invention is the provision of a garment hanger cover which is constructed from a single blank of cardboard which may be folded about a wire garment hanger to enclose the same to enable only the wire hook to project therefrom for suspension purposes, the cover being secured in position by interlocking means formed from the cardboard blank to avoid the use of clips or other separate fastening devices.

With these and other objects in view, the invention resides in the novel construction, combination and arrangement of parts, the essential features of which are hereinafter fully described, are particularly pointed out in the appended claims, and are illustrated in the accompanying drawing, in which:

Figure 1 is a front elevational view of my improved garment hanger.

Figure 2 is a rear elevational view thereof.

Figure 3 is a top plan view.

Figure 4 is an enlarged vertical sectional view on the line 4—4 of Figure 1.

Figure 5 is an enlarged horizontal sectional view on the line 5—5 of Figure 1.

Figure 6 is a plan view of the cardboard blank from which the hanger cover is constructed.

Referring to the drawing by reference characters, 10 designates a conventional type of wire garment hanger which includes a hook 11 from which outwardly and downwardly diverging arms 12—12 extend, and which arms are joined at their outer ends by a cross bar 13. The arms 12—12 and cross bar 13 form a substantially triangular shaped frame, the arms serving to support a coat, vest, dress, or like garment, while the cross bar is intended to support pants, ties,

skirts or the like when passed thereover. Such construction of hangers are inexpensive of manufacture due to the fact that they are formed from a single length of wire but the same are unsatisfactory due to the narrow gage wire which 5 tends to crease the garment hung thereon. It is therefore the purpose of this invention to apply a cover or jacket to such type of wire hanger to avoid the above objection, and to provide ample surface on which an advertisement may 10 appear.

The cover or jacket is designated in its entirety as at 14 and by particular reference to Figure 6 of the drawing, it will be seen that the same is constructed of a single blank of stiff bendable 15 material A preferably cardboard. The blank is irregular in plan but somewhat of a general triangular shape and which includes a triangular shaped front wall 15 having a downwardly projecting extension piece 16 coextensive with its 20 lower edge and which extends thereacross. The inclined sides of the triangular shaped front wall 15 are separated from substantially triangular shaped rear flaps 17 and 18 by double score lines 19 and 20 respectively. The top ends of the flaps 17 and 18 terminate in spaced relation adjacent the apex of the front wall 15, while the top end of the flap 17 is provided with a locking tongue 21 for interlocking in a slot 22 provided in the top end of the flap 18. The apex of the front wall 30 15 is notched inwardly as at 23 to accommodate the shank of the hook 11 of the wire hanger 10 while directly below and adjacent the notch 23, the front wall is provided with a slot 24 for a purpose to be hereinafter explained.

Cut from the front wall 15 adjacent the bottom edge thereof is a transversely disposed flap 25 adapted to fold downwardly over the extension piece 16 on the double transversely disposed score line 26. The flap 25 is provided with a transversely disposed slit 27 to receive the locking tongue 28 formed integral with the central portion of the extension piece 16 and foldable upwardly on the double score line 29.

The extension piece 16 beyond opposite sides 45 of the plane of the tongue 28 is provided with slots 30 which serve as necktie racks when the cover is in use upon the garment hanger 10.

When it is desired to enclose the hanger 10 with one of the covers or jackets 14, the hanger 50 10 is placed against the inner side of the front wall 15, the arms 12—12 of the hanger aligning with and being parallel to the double score lines 19 and 20 while the cross bar 13 aligns with and is parallel with the transverse score line 26. The 55

flap 25 is next folded inwardly and downwardly to enclose the cross bar 13 of the hanger and is held down by the bending of the tongue 28 upwardly and inserting the free end of the tongue 5 into the slit 27 as clearly shown in Figures 2 and 4 of the drawing. The terminal end of the tongue 28 underlies the cross bar 13 of the hanger, and the tongue assumes a bulged out appearance as illustrated in Figure 4. The flaps 17 and 18 are 10 next folded inwardly upon the double score lines 19 and 20, the tongue end of the flap 17 overlying the slotted end of the flap 18 and the tongue 21 being inserted into the slot 22 and interlocking with the walls thereof. The flaps 17 and 18 15 also assume a bulged appearance and coact to provide a rear wall in spaced relation to the front wall 15.

By providing double score lines along the lines of fold of the blank, it is possible to increase the 20 width of the fold to avoid sharp folded edges to prevent creasing of the garment hung upon the hanger.

The front wall 15 of the hanger on the outer side thereof may contain advertising indicia 31 as 25 shown in Figure 1 of the drawing, thus making the article attractive for advertising purposes.

When the flap 25 is folded into position over the cross bar 13 of the hanger, an elongated slot 32 is formed in the front wall and which slot 30 permits of the insertion of a pair of pants, skirt or other like apparel to be inserted therethrough and hung upon the extension piece 16. It will 35 of course be understood that a coat, vest, dress or other like garment may be supported by the inclined sides of the cover and that neckties may be hung upon the racks 30.

The slot 24 provided in the front wall 15 permits of the insertion of the hook end of a rod to engage beneath the apex portion of the wire 40 hanger 10 in instances where the hanger may be hung out of reach and it is desired to remove the hanger from its hung position.

While I have shown and described what I consider to be the most practical embodiments of 45 my invention, I wish it to be understood that such changes and modifications as come within the scope of the appended claims may be resorted to if desired.

Having thus described the invention, what I 50 claim as new and desire to secure by Letters Patent of the United States, is:—

1. An article of the class described comprising in combination, a wire garment hanger having a triangular shaped frame, a cardboard jacket including a front wall, a pair of rear flaps integral

with said front wall and folded on lines parallel to and over the inclined sides of said triangular shaped frame to a position rearwardly of said front wall, and interlocking means between said rear flaps for securing the same together, a transversely disposed flap cut and bent from said front wall and folded downwardly over the cross bar of said triangular shaped frame, an extension piece depending from said front wall, and a tongue bent upwardly from the mid portion of 10 said extension piece and entering a slot provided in the transversely disposed down turned flap. 5

2. A jacket for attachment to a garment hanger comprising a single blank of bendable cardboard 15 cut and scored to provide a triangular shaped front wall, a pair of bendable triangular shaped rear flaps coextensive with the inclined sides of said front wall, coacting interlocking means at the top ends of said rear flaps for securing the 20 flaps together when they are bent rearwardly and downwardly over the inclined sides of a garment hanger, a transversely disposed flap cut from said front wall and adapted to be folded downwardly over the cross bar of a garment hanger, an extension piece depending from said front wall, and a tongue on said extension piece at the mid portion thereof adapted to be folded upwardly for locking engagement within a slot provided in said transversely disposed flap when the same is in 30 bent down position.

3. A jacket for attachment to a wire garment hanger comprising a single blank of bendable cardboard 35 cut and scored to provide a triangular shaped rear flaps foldable inwardly over said front wall along score lines parallel to the inclined sides of said front wall, the wider ends of said triangular shaped rear flaps being disposed in close proximity to each other adjacent the apex of said 40 front wall, a hook tongue at the wider end of one of said rear flaps adapted to enter a slot in the adjacent end of the other rear flap when the flaps are folded over said front wall, an inwardly 45 foldable elongated flap cut from said front wall, the opening left by the formation of said elongated flap constituting a trousers receiving opening, said triangular shaped rear flaps adapted to lie clear of the opening when folded over said front wall, 50 and a tongue coextensive with said front wall at the mid portion thereof and foldable inwardly for insertion in a slot provided in said elongated flap.

PHILIP FRIEDMAN. 55
